PLATING ATTACHMENT FOR FULL-FASHIONED KNITTING MACHINES

Walter Hartmann, Paterson, N. J., assignor to
Alfred Hofmann, Inc., West New York, N. J.

Application November 7, 1939, Serial No. 303,195

10 Claims. (Cl. 66—129)

The present invention relates to the art of plating full-fashioned knitted stockings and primarily aims to provide an attachment which may be readily associated with an ordinary full-fashioned knitting machine to control the plating frictions for locking and unlocking the same and thus functioning in an automatic manner to apply the necessary pressure to the plating frictions during the plating operation, and to release the tension or drag on said frictions when not needed.

The art of plating full-fashioned knitted stockings is known as the process of lining the stocking, or certain parts thereof, by feeding a thread of a characteristic different from the body yarn so that said thread becomes placed under the body yarn and appears on one side of the fabric only. Plating under the present-day practice is limited chiefly to the reinforcement of the high heel sections, heel tabs, sole, and toe of the stocking, and the most frequent and important application of the principle is to use silk on the outside and reinforce it with a cheap material, such as cotton, on the inside.

In order to obtain good plating, it is necessary that the inner cotton thread be laid over the outer silk thread because otherwise the fabric becomes misplated and appears "speckled" when dyed due to the difference in the dye-absorbing properties of the two threads or yarns. The plating or cotton thread must be laid over the silk body yarn because, during the process of knitting, the right side of the fabric is underneath. It has been found that in order to assure the proper relationship of the two threads or yarns when laying the same, the plating carrier must always follow the main carrier.

The greatest difficulty in maintaining the main and plating carriers in their proper relationship is encountered during the plating of the high heel sections, because at least three carriers must then be used, one carrier threaded with the body yarn being intended to reciprocate over the entire width of the fabric, and two plating carriers, each threaded with a plating yarn, being intended to reciprocate respectively over the left and right high heel sections at the side portions of the fabric.

As is well known in the art, reciprocating motion is imparted to the plating carriers as well as to the main carrier by means of friction boxes, all mounted on a single friction rod. This friction rod has a constant uniform stroke of approximately 18", whereas the friction boxes controlling the plating carriers are limited in their stroke,

the distance travelled by said friction boxes generally varying from $\frac{1}{2}$ " to 3". Accordingly, there must be considerable slippage between the friction rod and plating friction boxes, which creates a drag, tending to displace the carriers and consequently increasing the possibilities of misplating and imperfect fabric.

The detrimental effects of this drag have multiplied with the increased length of present-day machines due to the increase in the length of the carrier rods and the increase in the number of carriers, with the result that the inertia of these parts has become so great that extremely tight friction is needed in order to assure the correct relationship of the carriers during the plating operation.

As a consequence of the tightened friction, the drag increases, and considerable heat is generated which expands the friction rod, entails undue wear and tear, and causes variations in the friction tension, necessitating slowing down of the machine, which unavoidably brings about a loss of production and a rise in cost.

It is, therefore, the primary object of the invention to provide a plating attachment capable of eliminating most of the drag normally imposed upon the plating friction boxes after they are no longer needed to move the carrier rod.

Another object of the invention resides in the provision of a plating attachment operating to prevent a loss of power in the machine at a point where the drag occurs, thereby obviating the necessity of slowing down the mechanism and, accordingly, eliminating resulting loss in production.

It is also an object of the invention to provide a plating attachment constructed to prevent wear on the friction rod, friction boxes, and associated parts, resulting in a saving in maintenance cost.

Other important objects and advantages of the invention will be in part obvious and in part pointed out hereinafter.

In order that the invention and its mode of operation may be readily understood by those skilled in the art, I have, in the accompanying drawings and in the detailed description based thereupon, set out a possible embodiment of the invention.

In these drawings:

Figure 1 is a diagrammatic plan of the several cooperating elements constituting the invention as applied to a flat or full-fashioned knitting machine; the elements being shown in their relative positions at the extreme left stroke of the "Coulier" motion.

Figure 2 is a view similar to Figure 1, but show-

ing the elements in their relative positions at the extreme right end stroke of the "Coulier" motion.

Figure 3 is a sectional elevation through a portion of the knitting machine showing the slur bar, friction rod, and carrier bars, and having certain elements of the invention illustrated in conjunction therewith.

Figure 4 is a plan view of one of the improved friction boxes.

Figure 5 is a front elevation of the same.

Figure 6 is a longitudinal section taken on line 6—6 of Figure 5.

Figure 7 is a vertical section taken on line 7—7 of Figure 5.

Figures 8, 9, 10, 11, 12, and 13 are diagrammatic illustrations of the various successive relative movements of the carrier bars and their carriers, the friction rod, and the plating frictions.

Referring more particularly to the drawings, wherein like characters of reference will designate corresponding parts throughout the several views, it is to be understood that I have shown only those parts of a full-fashioned hosiery knitting machine which are essential to a clear comprehension of the invention, the knitting machine itself being of the usual standard construction and operating in the manner well known in the art.

In Figures 1 and 2 of the drawings are shown, more or less diagrammatically, the related parts of the machine adapted to co-function during the process of plating. In these figures, the main carrier, which is threaded with the body yarn, is designated at 20; the left hand plating carrier, which is threaded with a plating yarn, is designated at 22; and the right hand plating carrier, which is also threaded with a plating yarn, is designated at 24. Of course, it will be understood that, whereas only the minimum number of carriers for one knitting section has been shown for illustration purposes, an equal number of carriers is supplied for each knitting section throughout the entire length of the machine.

The carriers 20, 22, and 24 of all the knitting sections are individually supported on separate reciprocable carrier bars, that is, a main carrier bar, indicated at 26, and two plating carrier bars, indicated at 28 and 30 respectively. The main carrier bar 26, supporting the main carrier 20, is connected with a main friction box 32 of the usual well known construction and in frictional engagement with the friction bar 34 mounted for longitudinal reciprocation through the function of the ordinary well known Coulier motion mechanism (not shown). The plating carrier bar 28, supporting the left hand plating carrier 22, and the plating carrier bar 30, supporting the right hand plating carrier 24, are respectively associated with plating friction devices 36 and 38 which are also associated with the friction rod 34 and which will be described in detail hereinafter.

From the foregoing description, it will be appreciated that the reciprocation of the friction rod 34 is transmitted to the main carrier bar 26 and its carrier 20 by means of the main friction box 32 and to the plating carrier bars 28 and 30 and their carriers 22 and 24 by means of the plating friction devices 36 and 38. However, the reciprocating movements of the carrier bars 26, 28, and 30 are variably limited in relation to the reciprocating movement of the friction rod 34 as is usually done in this type of machine. For that purpose, the machine is provided with the

ordinary well known narrowing and pointex mechanisms, the narrowing mechanism including the left hand carrier narrowing nut 40 and the right hand carrier narrowing nut 42, and the pointex mechanism including the left hand pointex rack 44 and the right hand pointex rack 46.

As clearly represented in Figures 1 and 2, the main carrier bar 26 is provided with spaced stops 48 and 50 respectively disposed so that the stop 48 will engage the carrier nut 42, thus arresting said carrier bar 26 in the course of its movement to the left, that is, in the direction of arrow A, and the stop 50 will engage the carrier nut 40, thus arresting the carrier bar 26 in the course of its movement to the right, that is, in the direction of arrow B.

The plating carrier bar 28 is also provided with spaced stops 52 and 54 respectively disposed so that the stop 52 will contact the carrier nut 42 thus arresting said carrier bar 28 in the course of its movement to the left, that is, in the direction of arrow A, and the stop 54 will contact the left hand pointex rack 44, thus arresting said carrier bar 28 in the course of its movement to the right, that is, in the direction of arrow B.

Likewise, the plating carrier bar 30 is provided with spaced stops 56, 58 respectively disposed so that the stop 56 will contact the right hand pointex rack 46 thus arresting said carrier bar 30 in the course of its movement to the left, that is, in the direction of arrow A, and the stop 58 will contact the narrowing nut 40, thus arresting said carrier bar 30 in the course of its movement to the right, that is, in the direction of arrow B.

The carrier narrowing nuts 40 and 42 and the pointex racks 44 and 46 are in engagement with the usual reversely threaded spindles 60 and 61 operated by the well known narrowing and pointex motion mechanisms commonly provided on the knitting machine, but not shown herein, so that said nuts and racks may be moved towards and away from each other for the purpose of fashioning the stocking blank fabric F and shaping the high heel sections H¹ and H² thereof.

In accordance with the present invention, and as shown in the drawings, the plating friction devices 36 and 38 respectively, intended for the operation of the plating carrier bars 28 and 30, preferably comprise carrier bar engaging fingers 62 and 63 securely fixed to suitably shaped brackets 64 and 65 freely received on a supporting shaft 66 (Figure 3), said brackets being provided with friction box engaging portions 68 and 69. Disposed for frictional engagement with the friction bar 34 and arranged thereon on the opposite sides of the bracket portions 68 and 69 are pairs of complementary friction boxes, as indicated at 70a—70b, and 72a—72b.

As illustrated in Figures 4 to 7 inclusive, each of the friction boxes 70a—70b and 72a—72b comprises a frame casting 74 of substantially rectangular configuration, constructed to encircle the friction bar 34 and slide longitudinally with respect thereto, said casting consisting of side portions 76 and 78 and end portions 80 and 82, the end portions being slotted, as shown at 84, for the passage of the friction bar 34 therethrough, as will more clearly appear from Figure 6.

Positioned within the frame casting 74 to contact the opposite faces of the friction bar 34 are friction elements 85 preferably consisting of sec-

tions of leather over which are placed seating plates 88. Arranged over the plates 88 are depressable leaf springs 90 adapted, when depressed, to exert pressure upon said plates 88 and thus urge the friction elements 86 into positive frictional engagement with the friction bar 34.

In order to depress the leaf springs 90, there are preferably provided rigid U-shaped straps 92 fitted within the side portions 76 and 78 of the frame casting 74 to contact the leaf springs 90 on one side of the friction bar 34, the end portions 94 of said straps projecting outwardly of said casting on the other side of the friction bar to extend for a distance beyond the springs 90 on said other side of the friction bar.

Mounted on the projecting end portions 94 of the U-shaped straps 92, and disposed to extend transversely thereof, are pins 96 serving as pivots for swingable members 98, each having a pair of diametrically opposed fingers 100 and 102. As will clearly appear from Figures 5 and 6, the members 98 are so arranged that the fingers 100 thereof project over the leaf springs 90 on the corresponding side of the friction bar 34, said fingers 100 having adjustable elements 104 disposed for bearing contact with said springs, and the fingers 102 project in paralleling relationship over and in contact with a rockable multi-sided operating shaft 106 supported intermediately of said members 98 by means of suitable bearings 108 on the side portions 76 and 78 of the frame casting 74.

It will be noted that the angularly disposed sides of the operating shaft 106 extend to different levels with respect to its axis so that, upon rocking said shaft from one position to another, the fingers 102 will be raised or lowered, causing the members 98 to move for tightening or loosening the straps 92, thus depressing or relieving the springs 90 in contact therewith and, at the same time, causing the fingers 100 to move for depressing or relieving the springs 90 associated therewith, accordingly frictionally locking or releasing the friction box with or from the friction rod 34.

In accordance with the invention, the rocking of the shaft 106 of each friction box to lock or unlock the same is to be accomplished automatically during the operation of the knitting machine. For that purpose, one end of the shaft 106 is extended beyond its bearing 108 and has rigidly fixed thereto a dog 110, preferably having a general V-shaped formation. The adjacent portions of the bearing 108 and of the dog 110 are preferably formed with step sections, as shown at 111, said step sections cofunctioning to act as a stop for the dog 110 when in idle position. The dogs 110 of the friction boxes 70a—70b and 72a—72b are positioned to lay in the path of movement of separate tripping roller carrying arms 112a—112b and 113a and 113b, the arms 112a—112b being supported in spaced relationship on a relatively short shaft 114 so that the arm 112a cooperates with the dog of the friction box 70a, while the arm 112b cooperates with the dog of the friction box 70b, and the arms 113a and 113b being supported in spaced relationship on another relatively short shaft 115 so that the arm 113a cooperates with the friction box 72a while the arm 113b cooperates with the dog of the friction box 72b.

The shafts 114 and 115 are connected by means of brackets 116 to the usual slur motion mechanism of the knitting machine to be reciprocated

thereby in unison with the friction rod 34 and slur bar 117 and, for that purpose, the brackets 116, as shown in Figure 3, may be secured onto a connecting link 118 attached to said slur bar and conveniently formed with a yoke 119 adapted for engagement with a guiding shaft 120 extending longitudinally of the machine.

Attention is called to the fact that, whereas the special friction boxes 70a—70b and 72a—72b are identical in construction, the operating shafts 106 and the dogs 110 of boxes 70a and 72a and of boxes 70b and 72b are relatively arranged in different positions. For instance, in the position shown in Figure 1, which position is taken at the extreme left end stroke of the Coulier motion, while the dogs 110 are all tripped in the same direction, boxes 70a and 72a are locked to frictionally engage the friction rod 34, and boxes 70b and 72b are unlocked to frictionally disengage said friction rod. Conversely, it will be understood that when the dogs 110 are tripped to the position opposite to that shown in Figure 1, that is, to the position illustrated in Figure 2 which position is taken at the extreme right end stroke of the "Coulier" motion, the boxes 70a and 72a become unlocked, and the boxes 70b and 72b become locked.

The tripping of the dogs 110 is obtained through the relative movement of the tripping roller carrying arms 112a—112b and 113a—113b with respect to the boxes 70a—70b and 72a—72b, the movement of said arms in either direction being in excess to that of said boxes. The friction boxes 70a—70b and 72a—72b may be timed by providing each box with an adjustable stop, as indicated at 122a—122b, 124a—124b, said stops being disposed to come in contact with suitable fixed parts of the machine frame, such as represented at 126 128, and 130, to arrest the movement of the boxes 70a—72a when moving to the left, that is, in the general direction of arrow A, and of boxes 70b—72b when moving to the right, that is, in the general direction of arrow B, while in each instance the tripping roller carrying arms 112a—112b and 113a—113b continue in their movement with the Coulier motion. It is this movement of the tripping roller carrying arms in excess to the movement of the friction boxes in either direction which is utilized to trip the dogs for locking the respective friction boxes to time the same for operating at the beginning of each plating course and for unlocking the respective friction boxes to release the same from the friction rod at the completion of each plated course.

With the foregoing description in mind, and with particular reference to Figures 8 to 13 inclusive, the operation of the improved plating attachment when in use may be summarized as follows:

In Figure 8, the respective parts illustrated are shown in the same relative position as in Figure 1, that is, the position is taken at the extreme left end stroke of the Coulier motion just at the point when a stroke to the right, that is, in the general direction of arrow B, is to begin, it being assumed that the knitting of the stocking blank fabric F has progressed to, and started, the plated high heel sections H¹ and H². In this position, the friction bar 34 has reached the end of its movement to the left; the main carrier 20 and the left plating carrier 22 are located at their extreme left position, that is, in overlapping relation at the outer left selvedge S¹ of the fabric, since the main carrier bar 26 and the plating carrier bar 28 are held in their extreme left po-

sition, the respective stops 48 and 52 (Figure 1) being in contact with the right hand narrowing nut 42; the plating carrier 24 is located at its extreme left position, that is, at the inner selvedge S4 of the right high heel section H2, since the plating carrier bar 30 is held in its extreme left position, the stop 56 (Figure 1) being in contact with the right hand pointex rack 46; the friction boxes 70b and 72b are unlocked since the tripping roller carrying arms 112b and 113b have passed beyond and tripped the dogs 110 of said boxes 70b and 72b; and, the friction boxes 70a and 72a are locked, since the tripping roller carrying arms 112a and 113a have passed beyond and tripped the dogs 110 of said boxes 70a and 72a, the stops 122a and 124a being in contact with the fixed machine parts 126 and 128.

It is to be noted that the position of the friction boxes 70a and 72a in relation to the position of the bracket portions 68 and 69 is such that a certain amount of space X and X1 respectively exists therebetween. These spaces X and X1 represent the distance that the plating friction boxes travel before the plating carriers 22 and 24 start to move, thus permitting the main carrier 20 to acquire a sufficient lead over said plating carriers. It is also to be noted that a certain amount of space Y (Figure 1) exists between the stop 56 of the main carrier bar 26 and the left hand carrier nut 40, this space Y representing the distance travelled by the main carrier 20 across the fabric when laying a full course; and that a certain amount of space Z (Figure 1) exists between the stop 54 of the plating carrier bar 28 and the left hand pointex rack 44 and between the stop 58 of the plating carrier 30 and the left hand carrier narrowing nut 40, these spaces Z representing the distances travelled by the plating carriers 22 and 24 across the high heel sections H1 and H2 in laying a plating course.

With the parts in the relative position above described, the Coulier motion starts its movement to the right, that is, in the general direction of arrow B. Of course, it will be understood that at that moment the slur bar 117 and the friction rod 34 follow the movement of the Coulier motion. The main friction box 32, being operatively connected to the friction bar, moves therewith, accordingly sliding the main carrier bar 26 and the main carrier 20, which starts the laying of the body yarn. At that same moment, the friction boxes 70a and 72a being locked into frictional engagement with the friction bar 37, move therewith. The friction boxes 70b and 72b, although unlocked, will however travel with the friction rod since they are supported thereby and since there is no obstruction in their path of movement to prevent them from being carried along. The tripping roller carrying arms 112a—112b and 113a—113b being connected to the slur bar 117 also move in unison with their respective friction boxes 70a—70b and 72a—72b. As the movement to the right continues, the locked friction box 70a comes in contact with the bracket portion 68, as represented in Figure 9, whereupon the bracket 64 and its finger 62 join in the movement of the Coulier motion and thus move the plating carrier bar 28 with its carrier 22, which then lays its plating yarn over the left high heel section H1.

When the carrier 22 reaches the position shown in Figure 10, that is, the inner selvedge S3 of the high heel section H1, the carrier is stopped because, by that time, the stop 54 (Fig-

ure 2) has reached the left hand pointex rack 44, which prevents further movement of the carrier bar 28, accordingly arresting the finger 62, bracket 64, and friction box 70a. Thereupon, the dog 110 is tripped by the tripping roller carrying arm 112a which continues to move relative to the friction box 70a, thus unlocking said friction box. In this manner, the friction bar 34 may proceed without drag to move the main carrier 20 in the continued laying of the body yarn, as illustrated in Figure 11.

When the position illustrated in Figure 11 is reached, that is, when the main carrier 20 has passed beyond the right plating carrier 30, the friction box 72a contacts the bracket portion 69, whereupon the bracket 65 and its finger 63 are carried along with said friction box 72a, thus imparting movement to the plating carrier bar 30 so that the plating carrier 24 may lay its yarn over the right high heel section H2, as shown in Figure 12.

Upon reaching the position shown in Figure 12, that is, when the plating carrier 72b reaches the outer selvedge S2 of the high heel section H2, said carrier 72b is stopped by reason of the stop 58 (Figure 2) coming in contact with the left hand carrier narrowing nut 40. Therefore, further movement of the carrier rod 38, finger 63, bracket 65, and friction box 72a is prevented. However, the Coulier motion in its continuing movement to the right, causes the tripping roller carrying arm 113a to trip the dog 110 of the friction box 72a, consequently unlocking the friction box 72a. In reaching the end of the stroke to the right, represented in Figure 13, wherein the respective parts are shown in the same relative position as in Figure 2, the tripping roller carrying arms 112b and 113b trip the dogs 110 of the friction boxes 70b and 72b which have been arrested due to the stops 122b and 124b coming into abutting engagement with the fixed parts 128 and 130 respectively.

As will clearly appear from Figure 2, the position of the parts at the extreme right end stroke of the Coulier motion is reversed to that shown in Figure 1. Therefore, the friction bar 34 has reached the end of its movement to the right; the main carrier 20 and left plating carrier 24 are located at their extreme right position, that is, in overlapping relation at the outer right selvedge S2 of the fabric, since the main carrier bar 26 and plating carrier bar 30 are held in their extreme right position, the stops 50 and 58 being in contact with the left end narrowing nut 40; the left plating carrier 22 is located at the extreme right position, that is, at the inner selvedge S3 of the left high heel section H1 since the plating carrier bar 28 is held in its extreme right position, the stop 54 being in contact with the left hand pointex rack 44; the friction boxes 70b and 72b are locked, since the tripping roller carrying arms 112b and 113b have passed beyond and tripped the dogs 110 of said boxes; and, the friction boxes 70a and 72a are unlocked since the tripping roller carrying arms 112a and 113a have passed beyond and tripped the dogs 110 of said boxes 70a and 72a.

Accordingly, when the Coulier motion moves to the left to lay the succeeding course, the plating attachment will operate in the same manner as, but in the reversed order, hereinbefore described.

From the foregoing description of the improved plating attachment and its operation, it will be appreciated that the plating boxes operable to

drive the plating carriers are always unlocked when their movement with the friction bar is prevented so that there cannot be any detrimental drag between said plating carrier boxes and the friction bar. Because of this feature, the knitting machine may be operated at a relatively high rate of speed during the plating operation, since the danger of overheating of parts, the possibilities of carrier misplacements, and the likelihood of mistiming are obviated.

In concluding, it is pointed out that the particular construction of the embodiment herein shown and described is capable of certain modifications without departing from the gist of the invention. Therefore, any modification coming within the scope of the sub-joined claims is to be considered within the spirit of the invention.

What I claim is:

1. In combination with the reciprocating friction bar and reciprocable carrier bars of a full-fashioned knitting machine, a plating attachment comprising carrier bar engaging means, a pair of complementary friction boxes each disposed for frictional engagement with the friction bar and arranged to engage said carrier bar engaging means, and means operable for locking and unlocking said friction boxes relatively to each other whereby said carrier bar engaging means and the carrier bar in engagement therewith may be moved with the friction bar in one direction by one of said friction boxes, and in the other direction by the other of said friction boxes.

2. In combination with the reciprocating friction bar and reciprocable carrier bars of a full-fashioned knitting machine, a plating attachment comprising a carrier bar engaging finger, a bracket carrying said finger and mounted for slidable movements, a pair of complementary friction boxes each disposed for frictional engagement with the friction bar and arranged to engage said bracket to slide the same, and means operable for locking and unlocking said friction boxes relatively to each other whereby said finger and the carrier bar in engagement therewith may be moved with the friction bar in one direction by one of said friction boxes, and in the other direction by the other of said friction boxes.

3. In combination with the reciprocating friction bar and reciprocable carrier bars of a full-fashioned knitting machine, a plating attachment comprising a pair of friction devices each including a carrier bar engaging finger, a bracket carrying said finger and mounted for slidable movements, a pair of complementary friction boxes each disposed in frictional engagement with the friction bar and arranged to engage said bracket to slide the same, and means operable for locking and unlocking said friction boxes relatively to each other whereby said finger and the carrier bar in engagement therewith may be moved with the friction bar in one direction by one of said friction boxes, and in the other direction by the other of said friction boxes.

4. In combination with the reciprocating friction bar, reciprocating slur bar, and reciprocable carrier bars of a full-fashioned knitting machine, a plating attachment comprising carrier bar engaging means, a pair of complementary friction boxes, each disposed for frictional engagement with the friction bar and arranged to engage said carrier bar engaging means, and means carried by and movable with the slur bar for locking and unlocking said friction boxes relatively to each other whereby said carrier bar engaging means and the carrier bar in engagement therewith may be moved with the friction bar in one direction by one of said friction boxes, and in the other direction by the other of said friction boxes.

each other whereby said carrier bar engaging means and the carrier bar in engagement therewith may be moved with the friction bar in one direction by one of said friction boxes, and in the other direction by the other of said friction boxes.

5. In combination with the reciprocating friction bar, reciprocating slur bar, and reciprocable carrier bars of a full-fashioned knitting machine, a plating attachment comprising a carrier bar engaging finger, a bracket carrying said finger and mounted for slidable movements, a pair of complementary friction boxes, each disposed for frictional engagement with the friction bar and arranged to engage said bracket to slide the same, and means carried by and movable with the slur bar for locking and unlocking said friction boxes relatively to each other whereby said finger and the carrier bar in engagement therewith may be moved with the friction bar in one direction by one of said friction boxes, and in the other direction by the other of said friction boxes.

20 6. In combination with the reciprocating friction bar, reciprocating slur bar, and reciprocable carrier bars of a full-fashioned knitting machine, a plating attachment comprising a pair of friction devices each including a carrier bar engaging finger, a bracket carrying said finger and mounted for slidable movements, a pair of complementary friction boxes each disposed for frictional engagement with the friction bar and arranged to engage said bracket to slide the same, and means carried by and movable with the slur bar for locking and unlocking said friction boxes relatively to each other whereby said finger and the carrier bar in engagement therewith may be moved with the friction bar in one direction by one of said friction boxes, and in the other direction by the other of said friction boxes.

25 7. In combination with the reciprocating friction bar and reciprocating carrier bars of a full-fashioned knitting machine, carrier bar engaging means, a pair of complementary friction boxes, each disposed for frictional engagement with the friction bar and arranged to engage said carrier bar engaging means, and means operable for locking and unlocking said friction boxes relatively to each other whereby said carrier bar engaging means and the carrier bar in engagement therewith may be moved with the friction bar in one direction by one of said friction boxes, and in the other direction by the other of said friction boxes.

30 8. In combination with the reciprocating friction bar, reciprocating slur bar, and reciprocable carrier bars of a full-fashioned knitting machine, carrier bar engaging means, a pair of complementary friction boxes, each disposed for frictional engagement with the friction bar and arranged to engage said carrier bar engaging means, and means carried by and movable with the slur bar for locking and unlocking said friction boxes relatively to each other whereby said carrier bar engaging means and the carrier bar in engagement therewith may be moved with the friction bar in one direction by one of said friction boxes, and in the other direction by the other of said friction boxes.

35 9. In combination with the reciprocating friction bar, reciprocating slur bar, and reciprocable carrier bars of a full-fashioned knitting machine, carrier bar engaging means, a pair of complementary friction boxes, each disposed for frictional engagement with the friction bar and arranged to engage said carrier bar engaging means, and means carried by and movable with the slur bar for locking and unlocking said friction boxes relatively to each other whereby said carrier bar engaging means and the carrier bar in engagement therewith may be moved with the friction bar in one direction by one of said friction boxes, and in the other direction by the other of said friction boxes.

40 10. In combination with the reciprocating friction bar, reciprocating slur bar, and reciprocable carrier bars of a full-fashioned knitting machine, a plating attachment comprising a carrier bar engaging finger, a bracket carrying said finger and mounted for slidable movements, a pair of complementary friction boxes each disposed for frictional engagement with the friction bar and arranged to engage said bracket to slide the same, and means carried by and movable with the slur bar for locking and unlocking said friction boxes relatively to each other whereby said finger and the carrier bar in engagement therewith may be moved with the friction bar in one direction by one of said friction boxes, and in the other direction by the other of said friction boxes.

45 11. In a knitting machine of the character described, a reciprocating slur bar; a reciprocating friction bar; a reciprocable carrier bar; a friction box connectable on the friction bar and engageable with the carrier bar for driving the same in one direction of its reciprocable move-

ment; a friction box connectable on the friction bar and engagement with the carrier bar for driving the same in the other direction of its reciprocable movement; and means carried by the slur bar and operable to connect said friction box to the friction bar for the driving of the carrier bar in said directions, and to disconnect said friction box from the friction bar at the end of their driving of the carrier bar in said directions.

10. In a knitting machine of the character described, a reciprocating slur bar; a reciprocating friction bar; a reciprocable carrier bar; friction means on the friction bar acting on said carrier bar to drive the same in unison with the friction bar during a portion of its reciprocation in one direction of its reciprocable movement; means

5 carried by the slur bar and engageable with said friction means to release the same and interrupt its driving action on said carrier bar during another portion of the friction bar reciprocation in said one direction; other friction means on the friction bar acting on said carrier bar to drive the same in unison with the friction bar during a portion of its reciprocation in the other direction of its reciprocable movement; and means carried by the slur bar and engageable with said other friction means to release the same and interrupt its driving action on said carrier bar during another portion of the friction rod reciprocation in said other direction.

WALTER HARTMANN.
